UNITED STATES PATENT OFFICE.

JOHN T. WAIT, OF INDIANAPOLIS, INDIANA.

CHIMNEY-COWL.

1,859,551.

Specification of Letters Patent. Patented Nov. 23, 1920.

Application filed September 23, 1920. Serial No. 412,265.

To all whom it may concern:

Be it known that I, JOHN T. WAIT, a citizen of the United States, residing at Indianapolis, in the county of Marion and State of Indiana, have invented new and useful Improvements in Chimney-Cowls, of which the following is a specification.

This invention relates to improvements in wind deflectors or cowls for the chimneys of houses, particularly dwelling houses, where an adjacent roof or wall interferes with the draft by creating air currents that blow over and down the chimney in a manner to cause the issue of smoke into the rooms of the house of which the chimney is a part.

The object of this invention is to provide a simple and inexpensive wind-brake that protects the flue-opening and converts the otherwise objectionable currents of air into ones that will induce a partial vacuum and improve the draft.

I accomplish the above and other objects which will hereinafter appear, by the means illustrated in the accompanying drawing, in which—

Figure 1, is the sheet-metal lay-out ready for bending into the finished forms shown in the other figures of the drawing, along the dotted lines. Fig. 2, is a rear view, and Fig. 3, a top plan view of the finished article in operative position on a chimney, and Fig. 4 is a view in side elevation of a house-roof and chimneys in which the chimneys are provided with my invention, this view illustrating the obstructions adjacent to the chimneys which would otherwise interfere with the draft through the chimneys.

Like characters of reference indicate like parts in the several views of the drawing.

My invention is made of sheet-metal of substantially diamond shape cut out in the flat, as shown in Fig. 1. It has a split 5 extending from one corner, in to what will be the base-line of a hood in the form of a hollow half-pyramid 6, when the metal sheet is bent on the dotted line $a-c$, and then on the lines $a-b$, and $a-d$. The plates 50 7 and 8 will then lie in the same plane, and are adapted to rest upon the horizontal top of the chimney when in use. The corners are bent in opposite direction from hood 6, on the lines $e-e$, $f-g$, $f-h$, and $i-i$, respectively to form ears 10, lapping the outside of the chimney and extending past the first mortar-joint below the top course of

bricks, and are retained on the chimney, thereby holding the cowl in place, by nails 9, driven through the ears into the mortar- 60 joints under said ears.

The hood is applied with the closed side of the half-pyramid toward the roof or wall from whence the disturbing air currents originate, in the manner shown in Fig. 4. 65 The oblique sides of the member 6, and the outward slope of it as a whole, divides the interfering air-currents and deflects them upwardly and laterally of the flue-opening 70 in a manner to embrace and frictionally 75 contact the smoke-vapors issuing from the chimney and drag them outwardly and away from the flue-opening. This creates a partial vacuum in the latter which draws the waste products of combustion up from 80 below by their rising to fill it, and thereupon these in turn are carried away in the manner above described.

The device is very inexpensive to make, the shape of it makes it nest closely for 80 shipment in quantities, and it is readily and easily applied by anyone who can climb to the top of a chimney and drive four nails.

Commercially, the blank as shown in Fig. 1 may be more conveniently sold and 85 shipped in that form to be bent into the finished product by any local tin or sheet metal worker.

Having thus fully described my invention, what I claim as new and wish to secure by 90 Letters Patent of the United States, is—

1. A blank for chimney-cowls formed out of sheet metal in diamond shape with a split extending from one corner part way to the corner opposite. 95

2. A chimney cowl formed out of sheet metal bent to form a semi-pyramid with outside flanges at the base of the pyramid and ears depending from the flanges. 100

3. A chimney cowl formed out of sheet 100 metal bent into a semi-pyramid, and also bent to provide outside flanges at the base of the pyramid coextensive with each pyramid side, said flanges being separated from each other opposite the angle between the 105 two sides to form additional corners, there thus being two corners for each flange, all of said corners being bent down to form ears that contact the outside of the chimney when the cowl is in use, and means for fastening the ears to the chimney. 110

Signed at Indianapolis, Indiana, this the 13 day of Sept. 1920.

JOHN T. WAIT.
